UNITED STATES PATENT OFFICE.

JAMES OTIS CRAWFORD, OF OAKLAND, CALIFORNIA, ASSIGNOR TO JOHN KRODER AND HENRY REUBEL COMPANY, OF NEW YORK, N. Y., A CORPORATION OF NEW YORK.

DESIGN FOR A CURTAIN POLE.

Application filed October 16, 1926. Serial No. 19,393. Term of patent 7 years.

To all whom it may concern:

Be it known that I, JAMES OTIS CRAWFORD, a citizen of the United States, and a resident of Oakland, in the county of Alameda and State of California, have invented a new, original, and ornamental Design for Curtain Pole, of which the following is a specification, reference being had to the accompanying drawing, forming part thereof.

Figure 1 is a side view of a curtain pole showing my new design.

Figure 2 is a sectional view through Figure 1 on line 2—2, the same being on an enlarged scale and illustrating the ornamental arrangement of faces.

I claim:

The ornamental design for a curtain pole, substantially as shown.

JAMES OTIS CRAWFORD.
